INVENTOR:
Bert D. Gilson,
by Oliver O. Martin
HIS ATTORNEY.

UNITED STATES PATENT OFFICE.

BERT D. GILSON, OF CHICAGO, ILLINOIS.

CIRCULATION-PUMP ATTACHMENT.

Application filed October 4, 1920. Serial No. 414,609.

To all whom it may concern:

Be it known that I, BERT D. GILSON, a citizen of the United States, residing at Chicago, in the county of Cook and State of Illinois, have invented new and useful Improvements in Circulation-Pump Attachments, of which the following is a specification.

This invention relates to an internal combustion engine, and has particular reference to a water circulating pump for such engine.

In water cooled engines of the type specified it is quite common to place a pump in the cooling circuit for the purpose of accelerating the flow of the cooling medium. Some engines are designed to include such pump. Others, which are built to sell very cheaply, such as the engine of a Ford automobile, are not provided with such pump, but pumps are specially built for attachment to the latter type of engine, and the present invention is directed to a device for the engine of a Ford automobile. The problem of providing an efficient pump, attachable within the very limited space under the hood of such automobile, has been successfully solved, but it has heretofore been found quite difficult to provide attachable devices for aligning such pump to be driven by suitable rotating members of the engine.

With these conditions in view my invention consists in devices whereby the attachment of such pump is greatly facilitated, and a more perfect driving connection obtained. More specifically my object is the provision of a bridge, attachable with the pump and carrying all elements required in order to properly connect the pump to be driven from the engine. These objects and the further advantageous features of the invention are hereinafter fully described, and structures embodying the invention are illustrated in the appended drawing, of which:

Fig. 1 is a side elevation of an engine of the type referred to, and pump and pump connections are shown attached to the engine.

Fig. 2 is a plan view substantially in agreement with Fig. 1, and

Fig. 3 is a similar view illustrating additional features of the invention.

The numeral 1 denotes the engine water jacket, from which extend connections 2 to the top of the engine radiator (not shown). From the bottom of said radiator

rises diagonally a tube 3, whose upper end is clamped on the inlet duct 4^a of a circulation accelerating pump 4, through which the cooling medium returns to the water jacket, all as usual in practice. Said pump has a bearing 4^b for a drive shaft 5, and the latter connects with an extension 6 carrying at its outer end a pulley 7, said pulley in turn aligned to be driven from a suitable source. In the drawing a belt 9 is shown bent over the said pulley, over a pulley 16 of the fan shaft, and over a pulley 8 mounted on the engine crank shaft 8, but other driving connections may be provided to suit circumstances.

The pump is secured to the side of the water jacket by means of a pair of bolts 10, 11, said bolts seated in the perforations provided in the engine for supporting the usual inlet elbow of the tube 3, which elbow is first removed from its fastening and detached from said tube, whereupon the pump is attached, as specified. Between the base 4^c of the pump, and the boss 1^a of the water jacket is inserted the foot 12^a of a bridge 12, and the latter extends sidewise to the front of the engine, in order to support the front end of the shaft 6. Such supporting means may conveniently take the shape of a bearing box 13, in which the shaft 6 is rotatable, and which is provided with an integral stud 13^a, said stud projecting inwardly and seated in an elongated perforation 12^b of said bridge. Suitable elements, such as a threaded nut 15 and a clamping washer 14 engage said stud and serve to retain said bearing box firmly in aligned position.

Attention is directed to the shape of the bridge 12. It extends sidewise substantially in a straight line for about two thirds of its length, whereupon it makes an outward turn in order to bring the end portion supporting box 13 close to the center line of the pump shaft 5, 6. A boss 12^c is provided on the inner wall of the bridge, at the beginning of its outward turn, which boss bears against the side of the water jacket 1 and thereby serves to keep the bridge steady. It is also noticed that said bridge is made with a wide flange 12^d, which materially strengthens the structure.

The advantages of the structure described are readily appreciated by those versed in the art. The pump is shipped to the purchaser ready to attach with the two screws 10, 11, which simultaneously clamp the

bridge 12 in position, whereupon it is only necessary to mount the belt 9. The shafts 5 and 6 are operatively connected by means of a suitable flexible joint comprising an arm 17 of shaft 5 and an arm 18 rigid on the end of the shaft 6. Said arms take a position at right angles to each other, and their outer ends are secured to an intermediate disc 19, which latter is made of suitable material, such as leather. Flexible joints, substantially as described, are well known for combining shafts which are so hung that they cannot readily be mounted in perfect alignment, and they serve to make up for slight alignment variations between bearings, such as the box 13 and the pump bearing in the present structure.

Referring now to Fig. 3, I shall now describe means for further aligning the shafts. 20 The distance from the surface of the water jacket boss 1^a and to the spot against which the bridge boss bears may vary slightly, due to the fact that no two castings are exactly alike, and such variation may suffice 25 to throw the two bearings out of line. In order to correct such dislocation the box 20 is movable out and in, and for this purpose it is seated in an eccentric sleeve 21 and clamped in position by a nut 22. Said sleeve is provided with external screw threads engaging a threaded perforation of the bridge 23, and a slight turn of said sleeve suffices to advance or retract the box 20 sufficiently to correct the error of alignment.

Furthermore there is a small amount of play between the bolts 10, 11 and the perforations which said bolts engage, sufficient to tilt the pump slightly at the time of 40 mounting the pump and bridge, and thereby to throw the two shafts out of alignment in a vertical plane. In such case the nut 22 is again loosened and the sleeve rotated a slight amount, thereby raising or 45 lowering the box as much as required, and as said box is free to turn in the sleeve, it is obvious that the shafts may be quickly realigned, whereupon the nut 22 again is tightened.

50 Occasionally an engine casting may be found so imperfect that the boss 23^c does not reach said casting at all, in which case the pull of the belt will tend to put a strain on the bridge, which strain in turn may operate to throw the shafts out of alignment. For this purpose I introduce means 55 for adjusting said boss 23^c, and such means may conveniently take the shape of a set screw 25, seated in said boss and locked in adjusted position by a threaded nut 26.

The devices described above may be attached to an automobile engine of the type mentioned by the purchaser without any special tools except the wrench which always accompanies an automobile. When

clamped in position, by the two bolts mentioned, it will work satisfactorily on account of the flexibility of the joint in the shaft, and if more perfect alignment is desired by the user, he may readily obtain such in the manner indicated. In conclusion I wish to call attention to one more feature of my invention. A belt will stretch, and the belt 9 may become so slack that it will not drive the pump at full speed, and for this reason I have introduced means for maintaining said belt taut. It is noticed by referring again to Fig. 3, that the bridge 23 is made in two parts joined together by a hinge pin 27. If a slight slackness occurs, it is only necessary to readjust the screw 25, it being remembered that the flexible joint in the shaft 6 compensates for errors of alignment. Of course, if such readjustment is repeatedly performed, it will also become necessary to readjust the front bearing of said shaft. A strong spring 28 may conveniently be added for the purpose of maintaining said belt taut.

I claim:

1. The combination with an internal combustion engine and a circulating pump attachable to said engine, of a bridge attachable with said pump, and a bearing box for the pump shaft and adjustably seated in the outer end of said bridge.

2. The combination with an internal combustion engine and a circulating pump attachable to said engine, of a bridge fitted at one end for simultaneous attachment with said pump, a bearing box adjustably seated in the outer end of said bridge, a shaft extending from the pump and rotatable in said box, and devices on the end of said shaft for operatively connecting the pump to be driven by the engine.

3. The combination with an internal combustion engine and a circulating pump attachable to said engine, of a bridge insertable between the pump and engine, a bearing box for the pump shaft adjustably seated in said bridge, a pulley on the end of said shaft, a belt hung over said pulley and rotating members of the engine, and a projection on the bridge and bearing against the side of the engine for relieving the strain on the bridge caused by the pull of said belt.

4. An internal combustion engine, a pump attachable to said engine by means of a pair of bolts of the engine, a bridge insertable between the engine and pump and held clamped by said bolts, an adjustable bearing box carried by said bridge, and a flexible shaft extending from said pump and rotatable in said box, said shaft carrying elements co-operating with rotating members of the engine for driving said pump.

5. In an internal combustion engine, the combination with the inlet boss of the water jacket, said boss having threaded bolt sock-

ets, of a circulating pump, an independent bridge supporting the outer end of the pump shaft, said bridge provided with parallel machined faces insertable between said boss and the said pump, both pump and bridge simultaneously attachable to the boss by the bolts engaging the threaded sockets, there being sufficient clearance on said bolts to swing the outer end of the bridge to align said shaft.

6. The combination with an internal combustion engine, of a pump and a bridge for the pump shaft, said pump and bridge simultaneously attachable to the inlet boss of the engine water jacket, a pulley on said shaft, a belt operatively connecting said pulley with rotating members of the engine, and means incorporated in said bridge for maintaining said belt taut.

20 7. The combination with an internal combustion engine and an attachable circulating pump, of a bridge fitted at one end with parallel faces insertable between the base of said pump and the water inlet boss of the engine and provided at the outer end with a pump shaft bearing, means simultaneously clamping the pump and the bridge in position, said means permitting the outer end of the bridge to be swung vertically to align said shaft before tightening.

8. The combination with an internal combustion engine and a circulating pump mountable on the side of the engine water jacket, of a bridge fitted at one end for insertion between the pump and engine and shaped at the opposite end to support the outer end of the pump shaft, connecting devices for driving said shaft, and means seated in the bridge and adjustable to bear

against water jacket for the purpose of relieving the strain of said driving connections on the bridge.

9. The combination with an internal combustion engine and a pump attachable to said engine, of a bridge insertable between the pump and engine, the outer end of said bridge horizontally perforated, and a bearing box for the pump shaft mountable in said perforation and adjustable in all directions for the purpose of proper alignment.

10. The combination with an internal combustion engine having on one side a water inlet boss, of a pump attachable to said boss, and a bridge shaped for insertion between the pump base and the boss, said bridge extending forward along the engine casting, its outer end projecting outward into alignment with the pump shaft and fitted to support said shaft, the bridge movable relative to the pump in a vertical plane in order properly to align said shaft.

11. The combination with an internal combustion engine, a pump mountable on the side of said engine, and driving connections for said pump; of a bridge comprising an inner portion insertable between the pump and engine and an extension hinged to swing sidewise on said portion, said extension shaped to support the outer end of the pump shaft, a member adjustably seated in said extension for contacting with the side of the engine, and a resilient member urging the extension away from the engine for the purpose of maintaining said connections taut.

In testimony whereof I have hereunto affixed my signature.

BERT D. GILSON.
